Oakton, Va., and Thomas J. Keane, Bethesda, Md.,
assignors to Gardner Laboratory, Inc., Bethesda, Md., a
corporation of Maryland

Filed Apr. 13, 1967, Ser. No. 6,670

Term of patent 7 years

(Cl. D57—1)

FIG. 1 is a rear elevational view of a portable tri-stimulus colorimeter showing our new design;

FIG. 2 is a view in front elevation;

FIG. 3 is a view in elevation showing one side of the colorimeter;

FIG. 4 is a view in elevation showing the opposite side of the colorimeter; and

FIG. 5 is a top plan view.

The dominant portions of our design reside in the portions shown in full lines.

We claim:

The ornamental design for a portable tri-stimulus colorimeter, as shown and described.
